CIGARETTE EXTINGUISHER

Gus L. Boland and Joseph T. Bertolani,
Modesto, Calif.

Application October 18, 1950, Serial No. 190,742

1 Claim. (Cl. 131—256)

2

This invention is directed to, and it is an object to provide, a cigarette extinguisher of novel structure and function.

Another object of the invention is to provide a cigarette extinguisher which is especially designed for use in a motor vehicle.

A further object of the invention is to provide a cigarette extinguisher wherein the cigarette—when disposed in a receiver—is extinguished by subjecting the then inner and burning end of the cigarette to suction derived from the intake manifold of the vehicle engine; the rapid reverse air-flow through the cigarette, from the mouth end to the burning end, causing rapid extinguishing of said cigarette.

An additional object of the invention is to provide the cigarette extinguisher with a novel valve unit which is normally closed to prevent undesirable constant air entry into the intake manifold of the engine; such valve unit opening under the influence of manual projection of the cigarette into the receiver of the device, and the cigarette then being subject to the reverse air-flow, as aforesaid.

A still further object of the invention is to provide a practical and reliable cigarette extinguisher, and yet one which will be exceedingly effective for the purpose for which it is designed.

Still another object of the invention is to provide a cigarette extinguisher which is designed for ease and economy of manufacture.

These objects are accomplished by means of such structure and relative arrangement of parts as will fully appear by a perusal of the following specification and claim.

In the drawings:

Fig. 1 is a somewhat diagrammatic elevation of the device as in use on a motor vehicle; the instrument panel and the fire wall being shown in section.

Fig. 2 is an enlarged sectional elevation of the device in its normal position, with the valve unit closed.

Fig. 3 is a similar view, but shows the device in use, with a cigarette projected into the receiver and with the valve unit open.

Fig. 4 is a cross section on line 4—4 of Fig. 2.

Fig. 5 is a fragmentary sectional plan of the tubular sleeve unit, showing the parts thereof separated and before being assembled or coupled together with the stem-mounting cross bar shown in end elevation.

Referring now more particularly to the characters of reference on the drawings, the novel cigarette extinguishing device is indicated gen-

erally at 1, and may be mounted in the motor vehicle in a selected position by any suitable means, such as a securing clamp 2 attached to the bottom flange 3 of the instrument panel 4.

5 A suction hose 5 leads from the device 1 forwardly through the fire wall 6 of the vehicle, and thence is coupled by a fitting 7 in communication with the intake manifold 8 of the engine 9; all as clearly shown in Fig. 1.

10 The cigarette extinguishing device 1 is shown in detail in Figs. 2 to 5, inclusive, and such device comprises the following structure:

The numeral 10 indicates an inner stationary tubular body coupled at one end with the hose 5; such stationary body being the portion of the device to which the securing clamp 2 is preferably attached.

At the end opposite the hose 5 the stationary tubular body 10 is encompassed, in telescopic 20 relation, by an outer slidable tubular body 11 or sleeve which is slidable on said body 10 with a relatively close fit.

The tubular body 10, at the end portion within the tubular sleeve 11, is of reduced internal diameter whereby to form a longitudinal, reduced-diameter bore 12 and an annular internal valve seat 13.

25 A cross bar 14 is secured in the tubular sleeve 11 some distance outwardly of the adjacent end of the tubular body 10, preferably in the following manner: The sleeve 11 is of metal and is formed as two initially separate aligned sections 11a and 11b, the section 11a engaging the body 10. The opposite or outer end of section 11a is formed with an internal circumferential recess

30 R which receives the ends of the cross bar 14, as shown in Fig. 4. The other sleeve section 11b abuts against the adjacent end of the sleeve section 11a, preventing outward movement of the cross bar, and is formed with a reduced-size extension E which is press-fitted into the recess R to the sides of the bar 14; this extension being oppositely notched, as at N in Fig. 5, to clear the ends of the bar 14. In this manner the cross bar is rigidly supported against either rotative or axial movement in the sleeve. An axial stem

35 15 is threaded into such cross bar 14, as at 16, and thence extends through the bore 12 in clearing relation with the body 10 and has a valve head 17 having a forwardly tapered face 18 adapted to cooperate with the valve seat 13.

40 A helical compression spring 19 is disposed in the tubular sleeve section 11a in engagement between the cross bar 14 and the adjacent outer 45 end of the tubular body 10, normally urging said

tubular sleeve 11 outwardly and closing the forwardly tapered face 18 of valve head 17 against the valve seat 13.

Thus, normally the described valve unit is closed so that air cannot constantly flow through the device 1 and hose 5 into the intake manifold 8, which would be undesirable.

When it is desired to extinguish a cigarette 20 the same is manually projected into the exposed or outer end section 116 of the tubular body 11, which section is flared, as at 21, to provide a somewhat funnel-like receiver. The cigarette 20 is projected into such receiver with the burning end 22 foremost, as shown in Fig. 3. When such burning end engages the cross bar 14, continued thrusting on the cigarette 20 compresses the spring 19 and shifts the slideable tubular body 11 inwardly, opening the valve head 17; i. e. clearing the tapered face 18 from valve seat 13. When this occurs a suction imposed air flow travels through the device, causing a rapid, cold air flow through the cigarette 20, which together with a reduction in the temperature of the burning end of the cigarette due to direct contact thereof with the metal bar 14, extinguishes the same. Additionally, a slight twist on the cigarette while it is engaged against the cross bar 15 breaks away all of the ash, which is instantaneously sucked through the device and hose 5, delivering into the intake manifold 8.

As soon as the cigarette is extinguished it is removed from the device and placed in a conventional ash tray in the vehicle, and at such time the spring 19 returns the device to its normal position with the valve unit closed.

While the ash sucked from the cigarette is drawn into the engine manifold, we have demonstrated from actual use that no detrimental effect on the engine is had, since the amount of such ash is very small, and the ash is so fine and non-abrasive that it may be drawn past the intake valves of the engine without danger of damaging or clogging the same.

The described cigarette extinguishing device, while being simple in its structure and operation, is nevertheless most effective to accomplish quick extinguishing of a cigarette with a minimum of manual effort.

It should be noted that the extinguishing operation can be accomplished wholly by one hand, so that the driver of the vehicle can maintain the other hand on the steering wheel.

From the foregoing description it will be readily

seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claim.

Having thus described the invention, the following is claimed as new and useful, and upon which Letters Patent are desired:

A cigarette extinguishing device for a motor vehicle comprising a rigid tubular body adapted to be mounted in a fixed position on the vehicle, a conduit connected to the inner end of the body and adapted for connection to a source of suction on the vehicle engine, means in the body at its outer end portion forming a relatively small bore and an annular valve seat facing the inner end of the body, a sleeve slideable over the outer end portion of the body, a cross bar in the sleeve outwardly of said body, the bore of the sleeve outwardly of the cross bar being in the form of a flaring mouth of a size at the cross bar to receive the lighted end of a cigarette, a stem removably secured in the cross bar and extending thence inwardly through said relatively small bore in clearing relation therewith, a valve head on the inner end of the stem smaller than the bore of the body adapted to engage the annular valve seat, and a spring about the stem between the outer end of the body and the cross bar yieldably holding the valve seated; said lighted end of the cigarette when pressed against the cross bar sliding the sleeve inwardly to open the valve and enable suction in the conduit and body to act to draw lighted ashes from the cigarette to extinguish the cigarette.
